HORSESHOE

Daniel O. Snyder, Muney, Pa.

Application July 21, 1932. Serial No. 623,885

Claims 13. (Cl. 168—14)

This application is a continuation in part of my U. S. Patent application Serial No. 550,566, filed July 13, 1931 and allowed June 10, 1932.

- Like the preceding application, the invention relates to improvements in horeshoes having attaching pads of rubber or other yieldable material at their lower sides and said invention aims to provide a new and improved construction in which novel provision is made for quickly and easily attaching the pad to the shoe or detaching it, not only allowing replacement or interchange of worn pads, but allowing the pads to be quickly and easily detached whenever it is advisable to attach calks to the shoe.
- With the foregoing in view, the invention resides in the novel subject matter hereinafter described and claimed, description being accomplished by reference to the accompanying drawings.
- Fig. 1 is a top plan view of a shoe constructed in accordance with the invention.

Fig. 2 is a central vertical longitudinal sectional view on line 2—2 of Fig. 1.

Fig. 3 is a vertical transverse sectional view on line 3—3 of Fig. 1.

Fig. 4 is a perspective view of the pad detached from the metal shoe.

Fig. 5 is a perspective view of the metal shoe.

Fig. 6 is a perspective view of the pad reinforcing plate.

A preferred construction has been shown and will be specifically described, with the understanding however, that variations may be made within the scope of the invention as claimed.

- 35 A metal shoe 7 is provided, said shoe having its rear ends connected by a transverse bridge bar 8 which is integral with said ends. Both the upper and the lower edges of this bridge bar are provided with forwardly projecting flanges, the upper flange being denoted at 9 and the lower flange at 10. The upper flange 9 is formed with a central notch 11 and two notches 12 are formed in the lower flange 10, near the ends of the latter. Preferably, the bar 8 is forwardly thickened to some extent at a plurality of points, as shown at 13. At its front end, the shoe 7 is provided with an integral rearwardly projecting tongue 14, and for lightness a recess 15 may well be formed in said shoe in advance of said tongue. The usual toe flange 16 is preferably provided, nail holes 17 are formed at the usual places, and openings 18 are provided to allow attachment of calks if desired. When the shoe is to be used with the calks however, the pad hereinafter described, is left detached, and when

use of the calks is no longer required, these calks are detached and the pad is re-applied.

The pad is shown at 19, and the shoe 7 rests upon the peripheral portion of this pad. The upper side of the pad is provided with a portion 20 to fit within the shoe 7, and the lower side of said pad is preferably concave to decrease liability of slipping on wet or otherwise slippery surfaces.

The pad 19 is provided with a metal reinforcing plate 22 whose central longitudinal portion is upwardly stamped to provide a longitudinal ridge of arched form in transverse section. The longitudinal edges of the plate 22 are preferably bent downwardly and laterally to provide flanges 24 which assist materially in anchoring the plate in the pad 19. To further assist in plate anchorage and to tie together the rubber above and below the plate 22, openings 25 are provided in said plate to receive some of the rubber of which the pad is constructed.

Under the front portion of the ridge 23, the pad 19 is recessed as shown at 26, allowing the open front end of said ridge to receive the tongue 14. The rear end of the plate 22 is provided, at 27, on opposite sides of the ridge 23, with rearwardly projecting portions 27. These portions 27 lie normally against the lower side of the flange 9, and this flange is preferably recessed somewhat at its lower side, as shown at 28 to receive said plate portions 27. The rear end portion of the ridge 23 is received normally in the notch 11 of the flange 9.

A transverse key 29 is disposed between the plate portions 27 and the lower flange 10 and contacts with these parts, to hold said plate portions 27 solidly up against the upper flange 9. The driving end of the key 29 is provided with a return bend 30 whose terminal snaps into one or the other of two recesses 31 formed in the rear side of the bridge bar 8. If the key be driven to the right, the return bend 30 snaps into one of the recesses, whereas if said key be driven to the left, said return bend engages the other of said recesses.

When the key 29 is withdrawn, the rear end of the pad may be pried downwardly out of engagement with the shoe, whereupon rearward shifting of said pad will withdraw the ridge 23 from engagement with the tongue 14, completely disconnecting the pad from the shoe. When the pad is being thus detached, the plate portions 27 move through the notches 12 when the rear end of the pad is lowered, and said pad is suitably recessed as shown at 32, to clear the forwardly

projecting flange 10. The rear end of the pad is also appropriately recessed at 33 to receive the key 29.

When applying the pad to the shoe, the pad is first so positioned that the tongue 14 will enter the front end of the ridge 23, whereupon said pad is forced forwardly and upwardly into position, the plate portions 27 then passing through the notches 12 and coming to rest in the recesses 23 in the lower side of the flange 9 at the same time the rear portion of the ridge 23 is received in the notch 11. When the key 29 is now driven into position, between the plate portions 27 and the flange 10, said key effectively locks the pad in engagement with the shoe and is itself held against accidental withdrawal by snapping of its return bend 30 into one or the other of the recesses 31.

While excellent results are obtainable from the details disclosed and they are therefore preferably followed, attention is again invited to the fact that variations may be made within the scope of the invention as claimed.

I claim:—

1. A horseshoe comprising a metal shoe, a pad having portions underlying and fitting within said metal shoe, a longitudinal reinforcing plate imbedded in said pad, said plate being provided with a central longitudinal upwardly stamped ridge portion open at one end of the plate, means carried by said metal shoe and received in said open end of said ridge portion to secure one end of the pad, and means engaging the other end of said plate for securing the other end of the pad.

2. A horseshoe provided with a rigid tongue projecting rearwardly from its front portion, a pad upon which the shoe rests, a reinforcing plate in said pad having an upwardly stamped longitudinal ridge portion whose front end is open and receives said tongue, and means for connecting the rear end of said plate with the shoe.

3. A horseshoe having a transverse bridge bar connecting its rear ends, said bridge bar being provided with a forwardly projecting flange at its lower edge, a pad upon which the shoe rests, a reinforcement in said pad and having a rearwardly projecting portion spaced above said flange, a transverse key between and in contact with said rearwardly projecting portion of said reinforcement and said flange, and means for connecting the front of said reinforcement with the shoe.

4. A horseshoe having a transverse bridge bar connecting its rear ends, said bridge bar being provided with upper and lower forwardly projecting flanges at its upper and lower edges respectively, a pad upon which the shoe rests, a reinforcement in said pad having a rearwardly projecting portion lying against the lower side of said upper flange and spaced above said lower flange, a transverse key between and contacting with said rearwardly projecting portion of said reinforcement and said lower flange, and means for connecting the front end of said reinforcement with the shoe.

5. A structure as specified in claim 4; said reinforcement having a central longitudinal ridge portion, said upper flange having a notch receiving the rear end of said ridge portion.

6. A horseshoe having a transverse bridge bar connecting its rear ends, said bridge bar being

provided with upper and lower forwardly projecting flanges at its upper and lower edges respectively, said upper flange having a notch between its ends and said lower flange having notches near its ends, a pad upon which the shoe rests, a reinforcing plate in said pad, said plate having a central longitudinal ridge portion whose rear end is received in said notch of said upper flange, said plate having rearwardly projecting portions at opposite sides of said ridge portion and movable through the notches in said lower flange, a transverse key between said lower flange and said rearwardly projecting plate portions and holding the latter against the lower side of said upper flange, and means for connecting the front end of said reinforcing plate with the shoe.

7. A horseshoe having a transverse bridge bar connecting its rear ends, said bridge bar being provided with upper and lower forwardly projecting flanges at its upper and lower edges respectively, said upper flange having a central notch, a pad upon which the shoe rests, a reinforcing plate in said pad having a central longitudinal upwardly stamped ridge portion whose rear end is received in said notch, a rearwardly projecting tongue on the front end of the shoe received in the front end of said ridge portion, and a transverse key between the rear portion of said plate and said lower flange and holding said rear plate portion against the lower side of said upper flange.

8. A structure as specified in claim 3; said key having a return bend at one end, the rear side of said bridge bar being formed with a recess into which said return bend snaps to hold the key against accidental removal.

9. A horseshoe pad, and a reinforcing plate embedded in said pad, said plate having a central longitudinal upwardly stamped ridge portion open at one end to receive a shoe-carried pad-attaching member.

10. A horseshoe pad, and a reinforcing plate embedded in said pad, said plate having a central longitudinal upwardly stamped ridge portion open at its front end to receive a shoe-carried tongue, the rear end of said plate having rearwardly projecting portions at opposite sides of said ridge portion.

11. A horseshoe having means at its front end for detachably holding a pad, said shoe having its rear ends connected by a transverse bridge bar, the lower edge of said bridge bar being provided with a forwardly projecting flange to support a pad-locking key.

12. A horseshoe having means at its front end for detachably holding a pad, said shoe having its rear ends connected by a transverse bridge bar, the upper and lower edges of said bridge bar being provided with forwardly projecting flanges respectively, the lower flange being adapted to support a pad-locking key.

13. A horseshoe having means at its front end for detachably holding a pad, said shoe having its rear ends connected by a transverse bridge bar, the upper and lower edges of said bridge bar being provided with forwardly projecting flanges respectively, said upper flange having a notch between its ends, said lower flange having notches near its ends and being adapted to support a pad-locking key.

DANIEL O. SNYDER.
